FOLDING CHAIR

Werner E. Clarin, Chicago, Ill., assignor of one-half to Abe J. Jacobson, Chicago, Ill.

Application July 1, 1942, Serial No. 449,211

5 Claims. (Cl. 155—142)

This invention relates to folding or collapsible chairs and more particularly to a linkage or bracing means adapted to support and lock a collapsible chair in open or extended position against inadvertent collapse.

Heretofore, one of the recognized disadvantages of certain types of collapsible chairs has been their inability to maintain themselves in open or extended position under all conditions of use, including both normal and extreme usage. It has been found that a collapsible chair will function satisfactorily and remain in fully extended position when the user of the chair is seated in normal position with his weight disposed on the center and forward portions of the seat, since pressure against these portions of the seat tends to force and hold the chair in fully extended position. However, when that weight is shifted to the rear portion of the seat under certain conditions of normal and extreme usage, the seat has a tendency to turn about its pivotal supports, causing the forward portion of the seat to raise upwardly and its rear portion to move downwardly and eventually effecting the folding of the chair to fully collapsed position. For instance, at public gatherings in auditoriums, gymnasiums and the like where chairs of this character are employed in great numbers, the occupants of such collapsible chairs in moments of great emotion or in order to improve their view have been known to stand up on the seats and to unthinkingly place their weight upon the rear portions of the seats, which action has caused the chairs to collapse unexpectedly and the occupants thereof to be thrown to the ground or floor, to their injury.

In view of this recognized danger, attempts have been made to provide means to prevent such inadvertent collapse under all conditions of normal and extreme usage. However, these attempts have proven unsatisfactory thus far, for varying reasons. In some instances the means provided wholly failed to accomplish their intended purpose, while in other instances their construction, although accomplishing to some degree of satisfaction the provision of a folding chair which was rendered noncollapsible under extreme conditions of usage, nevertheless was expensive and so cumbersome and complicated in operation that they were unacceptable commercially.

It is, therefore, one of the principal objects of my invention to provide a collapsible chair comprising means adapted to maintain said chair in fully open and extended position under all conditions of normal and extreme usage.

Another object of my invention is to provide a collapsible chair comprising means adapted to maintain said chair in open and extended position and to prevent inadvertent collapse of said chair when downward pressure is applied on the rear portion of the seat thereof.

10 A further object of my invention is to provide a linkage or bracing means adapted to support and lock a collapsible chair in extended position against inadvertent collapse under all conditions of normal and extreme usage which is of simple and inexpensive construction and by which said chair may be easily and quickly opened and maintained in locked position or may be, after use, readily released from locked position and returned to collapsed position.

15 A still further object is to provide a linkage mechanism for supporting and locking a collapsible chair in extended position against inadvertent collapse which comprises interengaging elements adapted to be moved automatically into interengaged and seat-supporting position merely by the application of the weight of an occupant on the seat and without any conscious act or understanding on the part of the occupant to accomplish said interengagement of the elements.

20 Other and further objects of the invention will appear as the description proceeds, reference being had to the accompanying drawings, in which:

25 Figure 1 is a right-side elevational view of a collapsible chair embodying the improved linkage and seat-supporting means comprising my invention and illustrating the chair in fully open or extended position.

30 Fig. 2 is an enlarged and fragmentary right-side elevational view illustrating the supporting linkage and seat-supporting means comprising my invention, both in locked and unlocked positions, and operably connected to the seat and the right rear leg of the chair shown in Fig. 1;

35 Fig. 3 is a fragmentary horizontal sectional view taken on the line 3—3 in Fig. 2 looking in the direction of the arrows, and illustrating the right-hand linkage and seat-supporting means in interengaged seat-supporting position;

40 Fig. 4 is a fragmentary horizontal sectional view taken on the line 4—4 in Fig. 3 looking in the direction of the arrows;

45 Fig. 5 is a horizontal sectional view taken on the line 5—5 in Fig. 1 looking in the direction of the arrows.

50 The collapsible chair illustrated in the drawings with which my invention is operably asso-

ciated is of the inverted Y type, this classification being derived from the angular manner in which the rear legs are disposed with respect to the front legs as viewed from the side. Generally, the chair illustrated in Figs. 1 and 5 comprises two rear legs 10 and 11 and two front legs 12 and 13 which are adapted to support a seat 14 when in fully open or extended position. The front legs 12 and 13 are connected by a reinforcing crossbar 15 and they are also integrally connected to a semicircular back frame member 16, the legs 12 and 13 and the back frame member 16 being, therefore, of one-piece construction. A web or back support 16^a is secured within in the back frame member 16. The front legs 12 and 13 are provided at their upper portions with rearwardly extending brackets 17, to which the rear legs 10 and 11, respectively, are pivotally connected. The rear legs 10 and 11 are also connected by two reinforcing horizontal cross-bars 19 and 20.

The seat 14, which is comprised of an outer frame member 14^a within which is mounted a relatively thin web or seat member 14^b, is pivotally mounted between the front legs 12 and 13 on pivot pins 22 and 23 which extend through the front legs 12 and 13 and through the sides of the seat frame member 14^a. The seat 14, the legs 10, 11, 12 and 13, the back frame 16 and the back support 16^a may be comprised of wood or the like, while the other attachments and fittings which have been or will be described hereinafter may be of metal or other sufficiently strong material.

The seat frame 14^a is maintained in spaced relation from the front legs 12 and 13 for relative pivotal movement by spacing brackets or angle plates 24 and 25 through which the pivot pins 22 and 23 extend. The seat 14 is also supported at its sides rearwardly of the pins 22 and 23 by link members 26 and 27, respectively, which are pivotally mounted at their rearward ends on pivot pins 28 and 29 secured on the upper portions of the rear legs 10 and 11, respectively, and extending from the inner faces thereof, and pivotally mounted at their forward ends to the seat frame 14^a on pivot pins 30 and 31 secured to the sides of the seat frame 14^a and extending outwardly therefrom. Because the construction of the link members 26 and 27 and the construction of the elements carried by the seat and adapted to engage the link members in seat-supporting position are identical, it is deemed sufficient for the purposes of the present description to set forth in detail the linkage mechanism and associated elements for only the right-hand side of the chair.

The forward end of the right-hand link 26 is provided with a longitudinally extending slot 32 through which the pivot pin 30 of the seat frame 14^a extends. The pivot pin 30 is provided with a head 30^a and a washer 33 is interposed between the head 30^a and the link member 26, this foregoing construction facilitating pivotal and longitudinal sliding movement of the pin 30 in the slot 32. The link member 26, near its rearward end, is formed with an offset angular portion 34 which serves to maintain the rear leg 10 in spaced relation from the seat frame 14^a, the pivot pin 28 extending through the offset portion 34 and through the rear leg 10 to which it is secured. On the extreme end of the link 26 rearwardly of the offset portion 34 but in the same plane of the portion of the link forwardly of the offset portion, there is a rearwardly extending lug 35

which slopes downwardly and forwardly, providing a vertical cam face 35^a. The link member 26 with its component parts is so constructed and arranged that it assumes a substantially horizontal position, when the chair is in fully open position, in substantially parallel relation vertically to and in substantially the same horizontal plane as the seat 14 so as to blend therewith and present a neat appearance when viewed from the side.

The seat frame 14^a on each of its sides is provided with metal reinforcing means which extend rearwardly from a point a short distance forwardly of the pivot pins 22 and 23 to the rear corners of the seat frame 14^a and around said rear corners to the back of the frame 14^a. Since the reinforcing means on both the left- and right-hand sides of the seat frame 14^a are identical, a description of only the right-hand reinforcing means will be sufficient. Specifically, the reinforcing or frame-strengthening means comprises an elongated member or plate 36 of L-shaped cross section, the vertical and horizontal portions of which fit flush against the outer vertical and lower horizontal faces, respectively, of the side of the seat frame 14^a. The reinforcing plate 36 is secured to the side of the seat frame 14^a by spaced rivets 37 and 38 which extend vertically through the seat frame 14^a and through the lower horizontal portion of the reinforcing plate 36. The rivet 38 also extends through the lower horizontal portion 24^a of the bracket 24 and serves to secure the bracket 24 to the seat frame 14^a in spacing position.

The rearward end of the reinforcing plate 36 at the right rear corner of the frame 14^a is provided with a vertical slot 39 which is adapted to receive the end 40 of a metal strip 41 extending at substantially right angles to the reinforcing plate member 36 along the back of said seat frame 14^a. The end 40 extends through the vertical slot 39 and is doubled back upon itself to form a hook around the vertical end portion 42 of the reinforcing plate 36. The metal strip 41 is positioned flush against the vertical face of the rear portion of the seat frame 14^a and its other end 43 is countersunk and secured therein by a screw 44.

By the aforesaid frame-strengthening means, the pressures and stresses to which the wooden seat frame 14^a is subjected during use when the chair is in fully open position are transmitted from the frame 14^a to the metal reinforcing plate 36. With the strengthening members extending a slight distance forwardly of the pivot pins 22 and 23, the fulcrum points of the seat 14, downward pressures applied to the front end of the seat 14 are transmitted through the frame 14^a to the reinforcing plate 36 and thence to the back portion of the frame 14^a through the metal strip 41. This transmission and distribution of pressures prevents the cracking of the side portions of the seat frame 14^a during use.

The reinforcing plate 36 is also provided with an elongated hooked member 45 at the upper portion of its extreme rearward end, this hooked member 45 being struck from the vertical body portion of the reinforcing plate 36 and bent forwardly and downwardly therefrom. This hooked member 45 is adapted to engage the top surface of the vertical lug 35 and to support the seat 14 against collapsible movement when downward pressure is applied to the rear portion of the seat 14 when in fully open position.

Another hooked member 46 is provided at the

bottom of the vertical face of the reinforcing plate 36 intermediate the pivot pin 30 and the offset portion 34 of the link 26, this hooked member 46 being struck from the lower horizontal face of the reinforcing plate 36 and being bent backwardly so as to project outwardly and then upwardly in parallel relation to the vertical face of the plate 36. This second hooked member 46 is adapted to engage the link member 26 at its lower edge intermediate the link slot 32 and the offset portion 34 and serves as a stop element for limiting the opening pivotal movement of the seat 14.

The foregoing arrangement of parts provides a collapsible chair which may be easily opened to extended position and locked therein against inadvertent collapse, and which also may be released from locked position and returned to a collapsed position with a minimum of effort. Commencing with the chair in the collapsed position, the forward portion of the seat, which is initially in substantially vertical position, may be grasped and pulled forwardly. As the front portion of the seat 14 is pulled forwardly it moves downwardly at the same time and its rear portion moves rearwardly and upwardly, the seat 14 turning on its pivot pins 22 and 23 during this operation. At the same time, as the seat 14 is being turned to substantially horizontal position, the rear legs 10 and 11 are swung outwardly or rearwardly away from the front legs 12 and 13 through the action of the links 26 and 27.

As the seat 14 nears the end of its opening pivotal movement, the right-hand edge 45^a of the hooked member 45 engages the cam face 35^a of the lug 35 at its lower end and rides upwardly on this cam face 35^a upon continued opening pivotal movement of the seat 14. When the hooked member 45 reaches the top of the lug camway 35^a, it is in registration or alignment with the top edge of the lug 35, and at this point the lower hooked member 46 engages the lower edge of the link member 26, thereby preventing further pivotal opening movement of the seat 14 and stopping the hooked member 45 in alignment with the top edge of the lug 35.

By application of additional downward pressure on the front end of the seat 14, which causes slight further spreading movement of the front and rear legs, the hooked member 45 and the lug 35 are slidably moved in a direction longitudinal of the link 26 into interlocking engagement with each other, as shown in Figs. 2, 3 and 4. In this interlocked position the hooked member 45 overlies the top edge of the lug 35 and is supported thereby when the chair is in fully open position. When the hooked member 45 is moved into engagement with the lug 35, the pivot pin 30 simultaneously slides to the forward end of the link slot 32.

The additional downward pressure by which the foregoing parts are interengaged in seat-supporting position may be applied not only manually on the front end of the seat 14, but also by the weight of an occupant assuming a seated position on the seat 14, which spreads the chair legs still farther and hence automatically moves the interengaging elements 35 and 45 into locked position. This automatic movement of the elements to locked position may be achieved without any conscious effort or understanding of the linkage locking mechanism of the chair by the occupant thereof, who is thereby protected against collapse of the chair re-

gardless of where downward pressure may be applied on the seat 14. For instance, if the occupant, in moments of great emotional stress or for other reasons, should stand or jump on the seat 14 and apply relatively great pressure to the rear portion thereof, collapsible pivotal movement of the seat 14 about the pivot pins 22 and 23 is prevented by the engagement of the hook member 45 of the seat plate 36 over the lug 35 of the link 26.

By a reversal of the above-described operation, the chair may also be rapidly returned to collapsed position. After the chair has first been rocked backwardly by a person standing behind the chair and the two rear legs 10 and 11 raised slightly from the floor, the legs 10 and 11 may be lowered with sufficient force against the floor at their rear edges so as to effect forward movement of the link 26 and consequent disengagement of the lug 35 from the hooked member 45. Simultaneously, the pin 30 moves relatively to the link 26 and reaches the rearward end of the slot 32. The hooked member 45 may also be released from supporting engagement with the lug 35 by merely striking rearwardly against the front edge of the seat 14 a slight blow with the hand, causing the same relative movement to released position, as above described. With the above parts in released position, the forward portion of the seat 14 may then be grasped and moved upwardly and rearwardly, the seat 14 turning about its pivot pins 22 and 23, until completely collapsed position is attained.

Although I have illustrated and described my invention specifically in the foregoing drawings and description, it is to be understood that changes and modifications may be resorted to without departing from the spirit and scope of the appended claims.

I claim:

1. In a collapsible chair having front and rear legs, the rear legs being pivotally connected at their upper portions to the front legs, and a seat adapted to be supported in substantially horizontal position from said legs and being pivotally mounted on said front legs; the combination of an elongated link member at each side of said seat having a pivotal connection to the adjacent rear leg of the chair at its rearward end and a pivotal and longitudinally slidable connection to said seat at its forward end, and means carried by said seat adapted to be moved in a direction longitudinal of the link members into engagement with the top edge of each of said link members and to support said seat in fully extended position against collapsible movement when downward pressure is applied to the rear portion of said seat.

2. In a collapsible chair having front and rear legs, the rear legs being pivotally connected at their upper portions to the front legs, and a seat adapted to be supported in substantially horizontal position from said legs and being pivotally mounted on said front legs; the combination of an elongated link member at each side of said seat having a pivotal connection to the adjacent rear leg of the chair at its rearward end and a pivotal and longitudinally slidable connection to said seat at its forward end, one of said links having a supporting lug at its rearward end, and a projecting member carried by said seat adapted to be moved in a direction longitudinal of the said one link member into engagement with said lug and to support said seat in fully extended position against collapsible movement when

downward pressure is applied to the rear portion of said seat.

3. In a collapsible chair having front and rear legs, the rear legs being pivotally connected at their upper portions to the front legs, and a seat adapted to be supported in substantially horizontal position from said legs and being pivotally mounted on said front legs; the combination of an elongated link member at each side of said seat having a pivotal connection to the adjacent rear leg of the chair at its rearward end, a pivotal and slideable connection to said seat at its forward end, and a longitudinally extending lug at its rearward end, said lugs having upwardly and rearwardly extending cam faces on their rearward ends, and projecting members carried by said seat adapted to engage and ride the cam faces of said lugs to the top edges thereof when said seat is being moved to extended position and to be moved in a forward direction longitudinally of the link members along the top edges of said lugs to interengaged position so as to support said seat in fully extended position when downward pressure is applied to the rear portion of said seat.

4. In a collapsible chair having front and rear legs, the rear legs being pivotally connected at their upper portions to the front legs, and a seat adapted to be supported in substantially horizontal position from said legs and being pivotally mounted on said front legs; the combination of an elongated link member at each side of said seat having a pivotal connection to the adjacent rear leg of the chair at its rearward end and a pivotal and slideable connection to said seat at its forward end, and interengaging means carried by said seat and interengaging means carried

by the rear portion of each of said link members adapted to be automatically moved in a direction longitudinally of the link members to fully interengaged position by the weight of the occupant on the seat and to support said seat in fully extended position against collapsible movement when downward pressure is applied to the rear portion of said seat, and stop means for limiting opening pivotal movement of said seat and for aligning said interengaging means prior to relative movement of said interengaging means longitudinally to interengaged position.

5. In a collapsible chair having front and rear legs, the rear legs being pivotally connected at their upper portions to the front legs, and a seat adapted to be supported in substantially horizontal position from said legs and being pivotally mounted on said front legs; the combination of an elongated link member at each side of said seat having a pivotal connection to the adjacent rear leg of the chair at its rearward end, and a pivotal and slideable connection to said seat at its forward end, and projecting members carried by said seat adapted to be moved in a direction longitudinal of the link members into engagement with the top edge of the rear portion of each of said link members and to support said seat in fully extended position against collapsible movement when downward pressure is applied to the rear portion of said seat, and stop means for limiting opening pivotal movement of said seat to align said projecting members with the top edge of each of said link members prior to relative longitudinal movement of said members to engaged position.

WERNER E. CLARIN.
